SEALING MEANS FOR WELL PACKERS

Neil T. Breaux, Houston, Tex.

Application February 14, 1949, Serial No. 76,318

8 Claims. (Cl. 166—12)

1

This invention relates to sealing means for well packers, or the like.

An object of the invention is to provide means for preventing flow of the packer sleeve when said sleeve is subjected to endwise compression. The sealing means is also useful on pistons or plungers which operate in cylinders.

It is another object of the invention to provide an expandable abutment with means for moving said abutment outwardly in close proximity with the surrounding well casing or cylinder wall, when pressure is applied to expand the packer, and to contract the abutment upon release of the packer to provide ample clearance between said abutment and well casing or other surrounding cylinder.

The invention also embodies novel means for supporting, expanding and contracting said abutment.

Other objects and advantages will be apparent from the following specification which is illustrated by the accompanying drawings, wherein:

Figure 1 is a side elevation, partly in section, of the assembly showing the packer collapsed and being lowered into the well casing.

Figure 2 is a side elevation, partly in section, of the lower end of the assembly.

Figure 3 is a side elevation, partly in section, showing the packer set, or expanded, and

Figure 4 is a side elevation, partly in section, of the lower end of the assembly, as shown in Figure 3.

Referring now more particularly to the drawings the numeral 1 designates an inner pipe whose upper end is threaded into the lower end of a tubular nipple 2 which, in turn, is connected to the lower end of the coupling 3. This coupling 3 is screwed into the lower end of the operating string 4 which extends to the ground surface. The inner pipe and nipple form a support for the assembly.

There is a packer supporting ring 5 which is pinned to the lower end of the nipple 2 by means of frangible pins 6 and which is sealed with said nipple by means of the annular seal 7 between them. Beneath the supporting ring 5 there is a resilient sleeve like packer 8 which is secured to said ring 5 in any selected manner, as by pins 9.

The lower end of the sleeve-like packer 8 is provided with a deep annular end slot 10 which is in alignment with an annular expander 11.

The slot 10 forms the lower end of the packer 8 into outer and inner annular lips and reinforcing the inner lip there is a metallic band 12 surrounding said inner lip and secured around the

2

outer side of the band there is a ring 13 whose upper margin forms an annular shoulder.

The upper end of the expander is provided with an inside annular shoulder 14 which hangs on the ring 13, when the assembly is in collapsed position to prevent detachment of said expander and maintain the same in operative relation with said sleeve.

The supporting ring 5 is provided with suitable outlet openings 15 which, in the present illustration, diverge upwardly to permit the escape of fluid between the sleeve-like packer 8 and the inner pipe 1 upon expansion of said packer.

Spaced beneath the packer there is a tubular cage 16 which surrounds and is spaced from the inner pipe 1 and while the assembly is collapsed the lower end of this cage is screwed onto the reduced upper end of a tubular reducing coupling 17 by means of coarse right hand threads.

The cage 16 is provided with vertically extended external sockets 18 to receive the friction blocks 19. These friction blocks are seated on coil springs 20 which hold the blocks outwardly in frictional contact with the outside casing, as shown in Figure 2.

The friction blocks 19 are retained in place by the upper and lower bands 21, 21 whose margins, adjacent the ends of said blocks, overlap said blocks and form stops to prevent detachment of the blocks.

Around the pipe 1 and seated on the upper end of the coupling 17 within the cage 16 there is a guide ring 22 which is externally tapered upwardly to form a guide for the cage, in assembly, to assure the intermeshing of its threads with the coarse external threads at the upper end of the coupling 17.

Fitted into the upper end of the cage 16 and suitably pinned therein there is a slip-supporting ring 23 and above this ring there are the wedge shaped slips 24 which are connected to said ring, and supported thereon, by the links 25 pivoted at their lower ends to the ring 23 and at their upper ends to the corresponding slips 24.

There is a tubular slip expander indicated generally by the numeral 26 and which surrounds and is spaced from the inner pipe 1 and whose external surface is upwardly flared and with which the slips 24 have sliding dove-tailed connections as 27.

The slips are prevented from detachment from the expander by means of pins 28 which are threaded into the expander and whose outer ends are engageable with upper inside shoulders 29 at

the upper ends of the slips 24, as indicated in Figure 2.

The external surface of the slips are provided with teeth which are pitched outwardly and downwardly, as shown, and upon downward movement of the expander relative to the slips said slips will be expanded into engagement with the outer casing as shown in Figure 3.

There is an approximately tubular inside coupling designated generally by the numeral 30 and whose upper end is provided with an inwardly extended flange 30a. Said upper end is also provided with an external annular groove indicated by the numeral 30b to receive the lower end of the expander 11.

The upper end of the slip expander has a wide inside annular groove 26a and is provided, at its upper end, with an inside annular flange 26b.

The lower end of the coupling 30 is provided with an external annular flange 30c which works in the groove 26a and is engageable with the flange 26b to prevent separation of parts.

There is a sectional retainer ring designated generally by the numeral 31 and which is formed of sections as 31a whose ends overlap thus at all times forming a continuous ring which, in effect, is expansible and contractile.

The upper end of the tubular coupling 30 is flared upwardly and the flared portion is formed with dovetailed grooves 30d. The inner sides of the sections 31a of the retainer ring are flared upwardly to conform to the flared portion of the coupling 30 and to ride thereagainst and screwed into these respective sections 31a are the screws 31b whose heads are dovetailed in the grooves 30d so as to form a slidable connection between the retainer ring and the coupling 30.

The upper end of the retainer ring 31 has an inside annular groove 31c to receive the lower end of the expander 11 when the assembly is in packer-expanding position, as shown in Figure 3.

The upper end of the slip expander 26 is provided with radial dovetailed notches 32 which receive correspondingly shaped downward extensions 33 carried by the respective sections 31a of the retainer ring so as to maintain these parts loosely connected together.

Incorporated into the inner pipe 1 and spaced beneath the tubular inside coupling 30 there is an enlarged coupling 34 of an outside diameter to fit snugly within the slip expander 26, as shown in Figure 1, and the lower end of this coupling 34 has an external annular upwardly facing shoulder 35.

Fitted snugly within the upper end of the expander 26 there is the tubular coupling support 36 whose upper end is provided with an external annular flange 36a which extends out into the groove 26a of the expander 26.

In operation the packer assembly is assembled, as shown in Figures 1 and 2, with the cage 16 screwed to the coupling 17 to maintain the slips 24 in their lower inner position and with the lower end of the expander 26 resting on the shoulder 35; and with the coupling support 36 resting on the upper end of the coupling 34. At the same time the inside coupling 30 is supported on the support 36 and the expander 11 is supported on said coupling, the sleeve-like packer 8 being pinned by the pins 6 to the nipple 2 and maintained in its upper collapsed position.

The friction blocks 19 however remain in frictional contact with the well casing, as shown in Figure 2, and the retainer ring 31 will be in its lower position and thus contracted, as shown in Figure 1.

When a point has been reached where it is desired to expand the sleeve-like packer 8 the operating string 4 may be turned to the right and the inner pipe 1 and the coupling 17 will be correspondingly turned so as to unscrew said coupling 17 from the cage 16. The inner pipe may then be lowered but the slips 24 will be held against downward movement so that said slips will be expanded outwardly into contact with the outer casing by said expander, as indicated in Figure 3. Meanwhile the sleeve-like packer 8, being pinned to the nipple 2 will also move downwardly and the expander 11 will be received by the slot 10 and the downward pressure on the expander 11 will move it downwardly thus forcing the coupling 30 downwardly until said expander 11 seats in the groove 31c thus causing the ring 31 and the sleeve expander to move downwardly wedging the slips 24 outwardly and stopping the downward movement of the ring 31 and as the coupling 30 moves downwardly relative to the ring 31 said ring 31 will also be expanded outwardly into close contact with the well casing.

Upon further movement of the operating string 4 downwardly the resistance of the sleeve-like packer 8, in its expanded position, will cause the pins 6 to shear and said nipple 2 will pass on down through the sleeve-like packer 8 and its lower end will enter the inside coupling 30 thus forming an inside support for said packer 8 and the lower end of the external coupling 3 will land on the upper end of the supporting ring 5 so that the desired weight may be applied to the packer 8 to fully expand it. The amount of this weight may be controlled by the operator.

The lower end of the expander 11 is downwardly and outwardly flared as indicated in Figure 1 so that the outer lip of the packer 8 will be forced outwardly into secure sealing relation with the well casing as is indicated in Figure 3.

As is well known rubber or similar resilient material when placed under compression will flow and in order to prevent this the sectional, expansible ring 31 has been provided with means for expanding said ring when the packer sleeve 8 is expanded, as above described, to effectively prevent the flowing downwardly of said sleeve to thus effect a more efficient seal.

The drawings and description disclose what is now considered to be a preferred form of the invention, however by way of illustration merely. The broad principle of the invention will be defined by the appended claims.

What I claim is:

1. In a well packer assembly, an inner pipe, a sleeve-like packer on said pipe, an expansible ring adjacent one end of the packer, expanding means within and connected to the ring and having a flared portion to expand the ring upon movement of the expander in one direction to close the space between the assembly and a well casing means operable by movement of the inner pipe in said one direction for anchoring the ring to the casing, said expander and ring forming an abutment, when the ring is expanded, means on the inner pipe for applying an endwise compressive force against the packer to move said end of the packer against the abutment and to thereby expand the packer and means on said inner pipe engageable with said anchoring means upon movement of said inner pipe in the other direction to release said anchoring means from the casing.

2. In a well packer assembly, an inner tubular support adapted to be connected to an operating

75

string, an expansible sleeve-like packer around said support, an expansible ring adjacent one end of the packer means releasably carried by the inner pipe and operable by downward movement of the inner pipe upon release from said means to anchor the ring to the casing, expanding means within and slidably connected to the ring for limited longitudinal movement relative to the ring, means on the support for applying endwise compression to the packer to move the packer against said expanding means and to actuate said means to expand said ring against a surrounding well casing to form an abutment and to prevent flow of the packer material when under compression and means on the inner pipe engageable with said anchoring means to release the anchoring means from the casing upon upward movement of the inner pipe.

3. In a packer assembly, an inner tubular support adapted to be connected to an operating string of pipe, means around the support engageable with a well casing and including casing engaging slips and an expander releasably connected to the support and operable by longitudinal movement of the support for moving the slips into engagement with the casing, a ring expander mounted on the slip expander, an expansible ring around the ring expander and adapted to be expanded thereby, upon longitudinal movement of the ring expander in one direction relative to the ring, into contact with the well casing; means forming a slideable connection between the ring expander and ring and operable upon limited longitudinal movement of the ring expander in the other direction relative to the ring to cause the ring to move out of contact with the casing, an expansible sleeve-like packer around the support spaced from the ring expander, means on the support for applying endwise compressive force to the packer upon longitudinal movement of the support, in one direction, to force the packer against the ring expander and to thereby expand the ring into contact with the casing to form an abutment for the packer to cause further expansion of the packer upon further movement of the support in said one direction and means on the support engageable with the expander upon movement of the support in the other direction to release the slips from the casing.

4. In a well packer assembly, a support, a sleeve-like packer on said support whose lower end has an annular slot, an expansible ring adjacent one end of the packer, expanding means within the ring having a flared portion to expand the ring upon movement of the expander in one direction to close the space between the assembly and a well casing means forming a slideable connection between the expander and ring and operable upon movement of the expander in the other direction to cause the ring to move out of engagement with the casing, means connected to the ring and operable by movement of the support in said one direction to anchor the ring to the casing, said expander and ring forming an abutment, when the ring is expanded, means on the support for applying an endwise compressive force against the packer to move said end of the packer against the abutment and to thereby expand the packer and a packer expander on the abutment positioned to be received by the slot upon such movement of the packer to further expand the packer and means on the support engageable with said anchoring means upon movement of the support in the other direction to release said anchoring means from the casing.

5. In a well packer assembly, an inner tubular support adapted to be connected to an operating string, an expansible sleeve-like packer around said support, means for securing one end of the packer to the support, an expansible ring adjacent the other end of the packer, expanding means within the ring means connected to the ring and operable by downward movement of the support for anchoring the ring to a surrounding casing, means on the support for applying endwise compression to the packer to move the packer upon movement of the support in one direction against said expanding means and to actuate said means to expand said ring against a surrounding well casing to form an abutment and to prevent flow of the packer material when under compression, means forming a slideable connection between said ring and said expanding means and operable upon movement of said support in the other direction to move the expanding means with the support to cause said ring to move out of contact with the casing, said securing means being disruptable, upon application of said compression to allow the support to move downwardly through the packer and means on the support engageable with said anchoring means upon upward movement of the support to release said anchoring means from the well casing.

6. In a well packer assembly, an inner tubular support adapted to be connected to an operating string, an expansible sleeve-like packer around said support, means for securing one end of the packer to the support for movement with the support, an expansible ring adjacent the other end of the packer, expanding means within the ring means connected to the ring and operable by downward movement of the support for anchoring the ring to a surrounding casing, means on the support for applying endwise compression to the packer to move the packer against said expanding means upon downward movement of the support relative to the ring to actuate said means to expand said ring against the surrounding well casing to form an abutment and to prevent flow of the packer material when under compression, means forming a slideable connection between said ring and expanding means and operable upon upward movement of the support relative to the ring to move the ring out of contact with the casing, said securing means being disruptable, upon application of said compression to allow the support to move downwardly through the packer, said support having an enlargement which enters the packer, upon such downward movement, and forms an internal support for the packer and means on the support engageable with said anchoring means upon upward movement of the support to release said anchoring means from the well casing.

7. In a packer assembly, an inner tubular support adapted to be connected to an operating string of pipe, means around the support engageable with a well casing and including casing engaging slips and an expander for the slips, a ring expander mounted on the slip expander, an expansible ring around the ring expander and connected to the slips and adapted to be expanded by the ring expander, upon longitudinal movement of the ring expander, into contact with the well casing, an expansible sleeve-like packer around the support spaced from the ring expander and having an end slot, means on the support for applying endwise compressive force to the packer upon longitudinal movement of the support, in one direction, to force the packer

against the ring expander and to thereby expand the ring into contact with the casing to form an abutment for the packer to cause further expansion of the packer upon further movement of the support in said direction, packer expanding means on the abutment adapted to be received by said slot, means forming a slideable connection between the ring and ring expander and operable upon longitudinal movement of the support in the other direction to move the ring out of engagement with said casing, and means on the support engageable with the slip expander upon longitudinal movement of the support in said other direction to release said slips from the casing.

8. In a device of the character described shaped to operate in a tubular member, an inner support, an expansible sleeve-like packing element around said support, an expansible ring adjacent one end of said packing element anchoring means operable by longitudinal movement of the support to anchor the ring to said tubular member, expanding means within the ring, means on the support adapted to cause the expanding means to expand said ring into contact with the tubular member, upon application of pressure to the opposite end

5 of the packing element to form a seal with the tubular member and prevent flow of the material of the element past the seal, means forming a slideable connection between the ring and expanding means and operable upon longitudinal movement of the support in the other direction to move the ring out of contact with the tubular member, and means on the support engageable with said anchoring means upon longitudinal movement of the support in said other direction to release said anchoring means from the tubular member.

10 NEIL T. BREAUX.
